VICTOR SODERSTROM, OF VIRGINIA, MINNESOTA.

SAFETY DEVICE FOR DIAMOND-DRILL-ROD COUPLINGS.

1,016,106.

Specification of Letters Patent.

Patented Jan. 30, 1912.

Application filed February 15, 1911. Serial No. 608,786.

To all whom it may concern:

Be it known that I, VICTOR SODERSTROM, of Virginia, St. Louis county, Minnesota, have invented certain new and useful Improvements in Safety Devices for Diamond-Drill-Rod Couplings, of which the following is a specification.

In the operation of diamond drilling it frequently happens that holes are drilled from twelve to fifteen hundred feet in depth, the drill passing through various strata in its descent, the drill rod being composed of hollow separable sections which are added on as the depth of the hole increases. These rod sections are generally about ten feet in length and are interiorly threaded at each end and a coupling is provided between the abutting ends of the contiguous sections to hold them together. Oftentimes in the drilling operation a coupling breaks. It is then necessary to remove the upper portion of the rod and contrive by some means to get hold of the lower portion and remove it and the drill from the hole; otherwise the diamond drill will be lost and it will be necessary to sink a new hole, unless the hole in which the drill is lost has been carried to the required depth. The walls of the hole at intervals, owing to the soft character of a stratum through which it may be drilled and the washing of the water, are frequently loosened and displaced to such an extent that a large cavity is formed and if the breakage of the coupling occurs in this cavity it is almost impossible to pick up the lower portion of the rod, as it will frequently tip over to one side out of line with the hole. The loss of a portion of a rod, particularly in a deep hole, involves considerable expense and obviously a contractor will not allow a diamond drill to be left in a hole without exhausting every effort to recover it.

The primary object, therefore, of my invention is to provide means which, when a coupling breaks, will allow the separated sections to be withdrawn immediately from the hole, thereby saving the drill and the lower sections without loss of time and labor.

My invention consists generally in a bolt fitting within the coupling and bridging the joint between the drill rod sections, and having means at each end which will serve to hold the broken, separated sections together.

Further the invention consists in various

constructions and combinations, all as hereinabove described and particularly pointed out in the claims.

In the accompanying drawings forming part of this specification, Figure 1 is a view of a portion of a hollow drill rod, partially in section, illustrating my invention applied to the coupling, Fig. 2 illustrates the device at work, the walls of the hole being washed away, as shown at one point, forming a cavity considerably larger than the diameter of the hole, Fig. 3 illustrates the device in operation when the breakage occurs in the coupling.

In the drawing, 2 and 3 represent contiguous sections of a hollow drill rod. These sections are internally threaded at 4.

5 is a coupling having nipples 6 and 7 formed thereon that are adapted to engage the threads in the ends of the sections 2 and 3, thereby securing them together. The coupling has a passage 8 therethrough communicating with the passage through the rods 2 and 3 to allow water under pressure to flow down through the rods to the drill to prevent it from heating and to wash away the material cut by the drill, the hole being of sufficient size, as indicated in Fig. 2, to allow the washings and the water to ascend outside of the pipe and escape at the top of the hole. The rods frequently break, usually at the point indicated in Fig. 3, and to hold these broken sections together I provide a bolt 9 having a head 10 at its lower end, the shank of the bolt 9 passing through the hole 8 and the head 10 contacting with the lower end of the nipple 6. This head is preferably provided with wings 11 which contact with the end of the coupling and prevent the head from entirely closing the passage. Normally, however, when the device is in use, the bolt will assume the position indicated in Fig. 1, the head 10, dropping away from the coupling and allowing the water to flow freely therethrough. The upper end of the bolt projects above the coupling and is threaded to receive an internally threaded sleeve 12 which has lugs 13 to rest upon the upper end of the coupling.

These lugs prevent the sleeve from closing the passage through the coupling when the drill is in use. The sleeve is also provided with external threads 14 so that in case of breakage of a rod above or below a coupling, 110 a rod having an internally threaded head thereon may be lowered in the hole until

the head engages the threads of the sleeve 12 and then by revolving the head it will make a threaded connection with the sleeve 12 and when this is done the lower portion 5 of the drill rod can be removed from the hole. I prefer to provide notches 15 in the upper end of the coupling to receive the lugs 13 and prevent the bolt from turning in the operation of connecting the threaded 10 head of the lifting rod to the threaded sleeve 12.

The device may be made in various sizes and of any suitable material.

The operation will be substantially the 15 same regardless of the diameter of the drill rod or the size of the drill or the coupling.

In various ways the details of construction may be modified and still be within the scope of my invention.

20 I claim as my invention:—

1. The combination, with hollow drill rod sections having threaded ends, of a coupling having nipples threaded to engage said ends and also having a longitudinal passage communicating with the passage through said rods, and means within said coupling passage and normally inactive, but becoming operative to hold said sections together in case of breakage of said coupling.

20 2. The combination, with hollow drill rod sections, of a hollow coupling uniting them, a bolt passing through said coupling and having a head at one end engaging said coupling and means for connection with a 35 lifting rod at the other end of said coupling,

said bolt being normally inactive but becoming operative upon breakage of said coupling for holding said rod sections together.

3. The combination, with hollow drill rod 40 sections, of a hollow coupling uniting their abutting ends, a bolt fitting within said coupling and having a head at one end, an exteriorly threaded sleeve at the other end of said bolt arranged to contact with said 45 coupling, said bolt being normally inactive and said sleeve and head permitting the water to pass freely through said coupling, said bolt becoming operative automatically upon breakage of said coupling for holding 50 said sections together.

4. The combination, with hollow drill rod sections, of a notched coupling uniting said sections and having a passage therethrough, a bolt fitting within said passage and having 55 means at one end engaging said coupling, an exteriorly threaded sleeve at the opposite end of said bolt having lugs to enter the notches in said coupling, said bolt holding said rod sections together in case of break- 60 age of said coupling, and said exteriorly threaded sleeve allowing the application of a tool thereto to lift the lower section in case of breakage above or below a coupling.

In witness whereof, I have hereunto set 65 my hand this 11th day of February 1911.

VICTOR SODERSTROM.
